UNITED STATES PATENT OFFICE.

NELSON MURPHY, OF DETROIT, MICHIGAN, ASSIGNOR OF ONE-FOURTH TO THOMAS L. HUTTON, OF DETROIT, MICHIGAN.

SAFETY DEVICE FOR PUNCH-PRESSES.

1,295,827.

Specification of Letters Patent. Patented Feb. 25, 1919.

Application filed November 5, 1917. Serial No. 200,279.

To all whom it may concern:

Be it known that I, NELSON MURPHY, a citizen of the United States of America, residing at Detroit, in the county of Wayne 5 and State of Michigan, have invented certain new and useful Improvements in Safety Devices for Punch-Presses, of which the following is a specification, reference being had therein to the accompanying drawings.

10 This invention relates to a safety device for punch presses, and such machines that have predetermined operations when set in motion, the operations being more or less automatic and to a degree beyond the control 15 of the operator of the machine after the machine has been started.

The primary object of my invention is to provide an automatic locking device adapted to predetermine the operation of a punch 20 press, when the device is actuated, said device confining the punch press to a single operation, and in this manner preventing a multiplicity of operations, due to carelessness on the part of the operator, breaking a 25 part of the machinery, or other causes beyond the control of the operator, which repeated operations may cause an operator's fingers to be severed or the operator otherwise injured.

30 A further object of this invention is to provide a simple, durable and inexpensive locking device for the driven shaft of a punch press, so that said shaft can only make one revolution and thereby lower and 35 raise, as a single operation, a punch die or other tool used in the machine.

My invention will be hereinafter specifically described and then claimed, and reference will now be had to the drawing, 40 wherein—

Figure 1 is a side elevation of a punch press provided with a safety device;

Fig. 2 is an enlarged longitudinal sectional view of a portion of the machine, showing 45 the locking device for the main shaft thereof;

Fig. 3 is a cross sectional view of the locking device;

Fig. 4 is a vertical sectional view of the 50 trip mechanism, and

Fig. 5 is a horizontal sectional view taken on the line V—V of Fig. 4.

In the drawing, there is illustrated, by the way of a suitable machine to which the

safety device may be applied, a punch press 55 1 having a reciprocable member 2 operated through the medium of a main shaft 3. This main shaft has a large loose gear wheel 4 adapted to be driven by a small gear wheel 5 on a suitable power shaft 6. A conventional form of clutch 7 controls the operation of the main shaft 3 by the large gear wheel 4, said clutch being spring pressed and having a pin 8 extending into a cam groove 9 in the periphery of the clutch 7. 60 A mechanism, including a pin rock arm 10, a reach rod 11, and a fulcrumed treadle 12 ordinarily control the operation of the clutch 7. For instance, and as shown, the clutch 7 is now out of engagement with the 65 large gear wheel 4 and the punch press is inactive. When the treadle 12 is depressed, the pin 8 is removed from the groove 9 and the spring of the clutch forces the clutch into engagement with the hub portion of 70 the large gear wheel 4 and establishes a driving relation between said large gear wheel and the main shaft 3. When the treadle 12 is released, the pin 8 enters the groove 9 and after one revolution of the 75 main shaft 3 the clutch 7 is automatically withdrawn or restored to normal position.

Sometimes the operator forgets to remove his foot from the treadle 12 and at other times the clutch mechanism breaks and in 80 either instance there are repeated operations of the press which are not only liable to injure the piece of work being performed upon, but the operator handling the piece 85 of work.

To provide the press with my improved device, it is necessary that the main shaft 3 or some rotatable member of the machine be provided with a notch 13, and seated on top 90 of the press, below the main shaft 3 is a 95 block 14 having a socket 15 for a locking arm 16. This locking arm is adapted to engage in the notch 13, somewhat similar to a pawl in a ratchet tooth and prevent further clockwise movement or rotation of the main 100 shaft 3. The locking arm 16 has the upper end thereof or an extension 17 thereof connected by a coiled retractile spring 18 to an upright or post 19 carried by the block 14, said spring holding the locking arm 16 normally in engagement with the main shaft 3, 105 so as to snap into the notch 13 when said notch reaches the end of the locking arm 16.

A suitable casing or housing 20 may inclose that portion of the main shaft 3 in proximity to the locking arm 16.

On the block 14 is a sheave or guide 21 for a cable 22 attached to the locking arm 16. The cable 22 extends downwardly under a sheave 23 attached to the side of a punch press and then extends upwardly and is connected to a trip member 24 in a casing 25 10 connected to the side of a punch press. The trip member 24 within the casing 25 has a spring pressed dog 26 adapted for engagement with a dog 27 at the side of a reciprocable member 28 slideable in the casing 25. 15 The dog 27 has a side pin 29 extending into an angularly disposed slot 30 in the side wall of the casing, and one end of the dog is pressed by a spring 31. Both of the dogs are beveled and at predetermined times are 20 adapted to recede.

Connected to the lower end of the reciprocable member 28 is a reach rod 32 and said rod is pivotally connected to the treadle 12 to be actuated in synchronism therewith.

25 In operation and when the treadle 12 is depressed, the member 28 is raised and as the dog 27 engages under the dog 26 the trip member 24 will be elevated thereby shifting the locking arm 16 so as to release the main 30 shaft 3. This operation takes place slightly in advance of the clutch 7 establishing a driving relation between the large gear wheel 4 and the main shaft 3, and in consequence of these successive operations, the 35 punch press is placed in operation.

As the dog 27 elevates the dog 26, the former gradually recedes by virtue of its pin and slot connection with the casing 25. Eventually the dog 26 is released and by 40 reason of the first operation the dog 27 is now above the dog 26, and the spring 18 holds the locking arm 16 against the rotating main shaft 3 so as to snap into the notch 13 when said notch reaches the end of the 45 arm 16. This will take place even though

the operator should retain his foot upon the treadle 12, and as a belt is generally employed for imparting movement to the power shaft 6, said belt will simply slip on the large pulley shown. Then again, should 50 anything happen to the clutch mechanism by which there may be repeated operations of the punch press, the locking arm 16 will prevent the same.

When the operator removes his foot from 55 the pedal 12, the dog 26 will recede and allow the dog 27 to assume its normal position beneath the same.

It is thought that the operation and utility 60 of the safety device will be apparent without further description, and while in the drawing there is illustrated a preferred embodiment of my invention, it is to be understood that the structural elements are susceptible to such changes as fall within the scope of 65 the appended claim.

What I claim is:—

The combination with a punch press having a main shaft, and a clutch adapted to automatically control the operation of said 70 shaft, of a pivoted locking arm engaging in said shaft to hold said shaft against rotation, a trip member connected to said locking arm, a reciprocable member confronting said trip member actuated in synchronism with 75 said clutch, and a pivoted spring pressed dog carried by each member with said dogs normally engaging each other and adapted to cause said trip member to be elevated by 80 said reciprocable member to withdraw said arm from within said shaft to release the same, and one of said dogs receding over the other when said reciprocable member assumes normal position.

In witness whereof I affix my signature in 85 the presence of two witnesses.

NELSON MURPHY.
